(57) **CLAIM**

We claim the ornamental design for a folding wagon, as shown and described.

DESCRIPTION

FIG. 1 is a front perspective view of a folding wagon according to the new design.

FIG. 2 is a bottom perspective view of the folding wagon shown in FIG. 1.

FIG. 3 is a right side view of the folding wagon shown in FIG. 1.

FIG. 4 is a left side view of the folding wagon shown in FIG. 1.

FIG. 5 is a front view of the folding wagon shown in FIG. 1.

FIG. 6 is a rear view of the folding wagon shown in FIG. 1.

FIG. 7 is a top plan view of the folding wagon shown in FIG. 1; and,

FIG. 8 is a bottom plan view of the folding wagon shown in FIG. 1.

The walls of the folding wagon are made of fabric. Features shown in broken lines in the drawings are not part of the claim.

1 Claim, 7 Drawing Sheets
